UNITED STATES PATENT OFFICE

ERNEST T. BECK, OF MERIDEN, CONNECTICUT, ASSIGNOR TO INTERNATIONAL SILVER COMPANY, OF MERIDEN, CONNECTICUT, A CORPORATION OF NEW JERSEY

DESIGN FOR A PLAQUE OR SIMILAR ARTICLE

Application filed July 10, 1931. Serial No. 40,488. Term of patent 7 years.

To all whom it may concern:

Be it known that I, ERNEST T. BECK, a citizen of the United States, residing at Meriden, county of New Haven, and State of Connecticut, have invented a new, original, and ornamental Design for a Plaque or Similar Article, of which the following is a specification, reference being had to the accompanying drawings, forming a part thereof.

Fig. 1 is a front view of a plaque or similar article showing my new design; and Fig. 2 is a side view of the same.

I claim:

The ornamental design for a plaque or similar article, substantially as shown.

ERNEST T. BECK.
